UNITED STATES PATENT OFFICE

129,161

DESIGN FOR A HAND SWITCH

Jack P. Fischer, Westchester County, N. Y., assignor to J. P. Fischer Inc., New York, N. Y.

Application May 31, 1941, Serial No. 101,238

Term of patent 7 years

To all whom it may concern:

Be it known that I, Jack P. Fischer, a citizen of the United States and a resident of the county of Westchester, State of New York, have invented a new, original, and ornamental Design for a Hand Switch, of which the following is a specification reference being had to the accompanying drawing, forming part thereof.

Fig. 1 is a plan view of a hand switch showing my new design.

Fig. 2 is a front view thereof.

I claim:

The ornamental design for a hand switch, substantially as shown.

JACK P. FISCHER.
